DEMODULATOR DEVICE FOR FREQUENCY
AND AMPLITUDE MODULATION

Edward H. Lange, Baltimore, Md.

Application April 3, 1944, Serial No. 529,359

18 Claims. (Cl. 250—20)

This invention pertains to receiving systems for receiving either frequency-modulated carrier waves or amplitude-modulated carrier waves, and more particularly to demodulator devices for such receiving systems, capable of demodulating either frequency-modulation or amplitude-modulation.

The principal object of this invention is to provide such demodulator devices with a maximum of economy of necessary electronic equipment and compartment circuit parts, with improved facilities for compensating amplitude-modulation, and improved facilities for tuning and for control of unmodulated signal amplitudes.

A first object of this invention is to provide a frequency-demodulator requiring but a single conventional type of electronic tube, and capable of operating upon a variable norm of signal strength of frequency-modulated signals, compensating audio-frequency variations of signal amplitude and permitting lower frequency, i. e. sub-audio frequency variations to pass uncompensated, and requiring no readjustment of circuit elements to attain compensation of amplitude variations when the average value of signal amplitude changes from one norm to another.

A second object of this invention is to provide a simple form of demodulator circuit with a control-impedance carrying the sum total of thermionic currents of both diode rectifying means employed for frequency-demodulation, to attain unidirectional control-voltages independent of frequency-modulation and directly proportional to the amplitude of carrier currents, for the essential controls of demodulation.

A third object of this invention is to utilize the control-impedance in a novel compensating system for compensating undesired variations of amplitude of the carrier currents during the reception of frequency-modulated carrier currents. In systems heretofore disclosed, such compensation is generally effected in relation to a definite norm of carrier current amplitudes, such that the norm or average value of the carrier current amplitudes is an essential part of a balance established, compensation being with reference to amplitude variations from a specific norm, and such that when the norm is changed, a new balance must be set up to attain compensation with reference to the new norm, thus requiring periodic adjustment for various magnitudes of the norm. In the present invention, the necessity of this periodic adjustment is eliminated, slow changes in the norm of insufficient rapidity to modify the acoustic resultant from the frequency-demodulated output-voltages are permitted; filter means

are employed to transmit voltages from the control-impedance which are a consequence of changes of carrier current amplitudes in the audio-frequency range, and employed to substantially annul the changes in the carrier current amplitudes of the carrier currents coupled with the resonance network of the demodulator, when such changes are sufficiently rapid to fall within the audio-frequency range.

10 A fourth object of this invention is to provide a control means for the average amplitude of carrier currents employed upon the demodulators, for regulating the maximum values of the demodulated output-voltages automatically in relation to the strength of received signals, applicable selectively for use during reception of frequency-modulated signals, or for use during reception of amplitude-modulated signals, or for both, and employing the control-impedance of this invention.

15 A fifth object of this invention is to provide a simple tuning means for tuning the resonance network of the demodulators to a predetermined centre frequency, employing the control-impedance of this invention and an electron-ray tube.

20 A sixth object of this invention is to provide automatic correction of tuning to coincidence with a predetermined centre frequency of the resonance networks of the demodulators, when demodulating frequency-modulation as well as when demodulating amplitude-modulation, and in a superheterodyne receiver having a mixer-device for reducing the carrier frequency, including a thermionic alternating current generator having a bias-voltage control means for controlling the frequency of the generator.

25 These objects, and others, are hereinafter pointed out in further detail, and will be better understood by reference to the drawing, and to the appended claims.

30 In the drawing,
Fig. 1 illustrates a demodulator for both frequency-modulation and amplitude-modulation, with means for compensating amplitude-modulation, means for regulating an average amplitude of carrier currents, selector means for selecting the above means, including means for selectively connecting an audio-frequency push-pull amplifier for amplifying either frequency-demodulated output-voltages or amplitude-demodulated output-voltages, and means for tuning the resonance network to a centre frequency coincident with the centre frequency of the carrier currents.

35 Fig. 2 illustrates a modification of Fig. 1, in which the grid-controlled thermionic conduct-

ance between an anode and common cathode of the thermionic tube of the demodulator, is connected with the primary windings of the resonance network only during reception of frequency-modulation.

Fig. 3 illustrates another modification of Fig. 1, in which a separate thermionic tube is employed for the rectifying diodes connected with the resonance network, and transfer-filter means is provided for transferring from the output-impedance for frequency-demodulated voltages to the bias-voltage control circuit of the mixer, steady bias voltages, independent of amplitude variations of the frequency-demodulated voltages, and proportional to the deviation of the centre frequency of the carrier currents from the centre frequency of the resonance network, for automatically modifying the generated frequency of the mixer-generator to annul the undesired deviation between said centre frequencies.

Fig. 4 illustrates certain quantitative relations with reference to the resonance networks, in relation to a centre frequency for the networks, and for the control-impedance of this invention, and tuning of the demodulators.

Fig. 5 illustrates a conventional type of mutual-conductance characteristic of super-control or variable mu types of thermionic tube, employable in connection with the dynamic-type of compensation for amplitude-modulation of this invention, in which an equilibrium of carrier current amplitudes is determined by the erasure of the original corrective stimulus, as distinguished from a static-type of compensation, wherein a fixed magnitude of change of carrier current amplitude causes a proportionately fixed magnitude of corrective stimulus, to maintain the frequency-voltage conversion sensitivity of the demodulator constant, while permitting changes in amplitude of the carrier currents.

Referring to Fig. 1, at 4 is an inductance coil, shunted by the variable condenser 19, the elements 4-19 forming a resonance circuit, which is coupled by mutual inductance with the primary coil 5; also at 3 is an inductance coil forming a resonance circuit with the variable condensers 18 and 17, and at 6 is a primary coil coupled by mutual inductance with 3. At 1 is a common terminal upon the resonance circuits 4-19 and 3-17. At 42 is indicated a mechanical inter-connection between the rotors of the variable condensers 19, 17, and 18, the condenser 18 being a spacer-condenser, for simultaneously spacing the resonant frequency of the resonance circuit 3-17 a predetermined frequency-interval from the resonant frequency of the resonance circuit 4-19, and for regulating the amount of the frequency-interval in relation to the magnitude of the resonant frequency. At 37 is a source of unidirectional voltage, having its negative terminal connected to the ground 36. At 10 is a thermionic tube having the diode-anode 12, diode-anode 13, anode 11, common cathode 14, control-grid 7, screen-grid 8, and suppressor-grid 9. The cathode 14 has the cathode terminal 16, and the common terminal 1 upon the resonance circuits 3-17 and 4-19 is connected through the control-impedance 2-21 to the terminal 16; control-impedance 2-21 has the resistance 2 shunted by the condenser 21. The terminal *a* of inductance coil 3 is connected through impedance 22-20 and conductor *d* to the diode-anode 12, likewise the terminal *b* of inductance coil 4 is connected through impedance 23-24 and conductor *k* to diode-anode 13; the impedances 22-20 and 23-

24 are made up of the respective equal resistances 22 and 23, each shunted by an equal capacitance, the resistance 22 being shunted by the condenser 20, and the resistance 23 being shunted by the condenser 24. The resistances 22, 23 are large in relation to the respective shunt capacitive reactances of 20 or 24, at the frequency of the carrier currents, to provide a large time-constant in relation to the half-cycle time of the carrier currents, sufficient to smooth out the rectified currents in resistances 22 and 23. The control-impedance 2-21 carries the total thermionic currents of both the diode-anodes 12 and 13, and likewise has a large time-constant sufficient to smooth out the voltages developed across the resistance 2, the control-impedance being discussed hereafter in further detail, and in reference to Fig. 4. Connected between the diode-anodes 12, 13, is the output-resistance for frequency-demodulated voltages, 52-52', consisting of the resistance 52 connected in series with the resistance 52', and having the mid-point *y* between these resistances connected to ground, at 36. Resistance 52 is connected to diode anode 12, through condenser 51 and choke-coil 29, and resistance 52' is connected to diode-anode 13, through condenser 32 and choke-coil 30. Choke-coils 29 and 30 each have a high reactance at the carrier frequency in relation to respective inductance coils 3 and 4, and the condensers 51 and 32 each have negligible reactance at audio-frequencies in relation to respective resistances 52 and 52', and serve as stopping condensers. Resistances 52 and 52' are equal. Condenser *h* is shunted across resistance 52, and condenser *j* is shunted across resistance 52'; these condensers serve to by-pass the small carrier frequency currents which traverse the choke-coils, around the resistances 52 and 52' respectively, that is, to substantially eliminate voltages upon 52 and 52' of carrier frequency. At S₁ and S₂ are switch-blades, capable of connecting respectively with terminals F₁ and F₂, for reception of frequency-demodulated voltages, or with A₁ and A₂, for reception of amplitude-demodulated voltages. At 35 is a bias-resistance connected from the cathode 14 to ground 36, for carrying the unidirectional current which flows from the anode 11 to the cathode 14 in tube 10, by reason of connection of anode 11 with the positive terminal of source 37. Resistance 35 is shunted by the bypass condenser 34, for by-passing alternating current components around resistance 35. At 25-26 is a transfer-filter for transferring voltage variations from the control-impedance 2-21 to grid control means, the reactance of condenser 26 at audio-frequencies being negligible in comparison with the resistance of 25. Condenser 26 and resistance 25, are connected in series, one terminal of resistance 25 being connected to ground 36, and one terminal of condenser 26 being connected to the common terminal 1. At 27-28-42, is a second transfer-filter, for transferring steady voltages from the control-impedance 2-21 to grid control means, the reactance of condenser 28 at audio-frequencies being negligible in relation to the resistance 27, and resistance 42. The resistance 27 is connected in series with the condenser 28, one terminal of the condenser 28 being connected to the cathode terminal 16, and one terminal of the resistance 27 being connected to the common terminal 1. Resistance 42, is shunted across condenser 28. The above described connections, and elements, apply also to Fig. 2.

In Fig. 1, the anode 11 is energized by connection through the primary coils 6 and 5 in series, to the positive terminal of the source 37. Suppressor-grid 9 is connected to cathode terminal 16, and screen-grid 8 is connected to a positive terminal upon the source 37, by the variable connector 38. Connected between the terminals 44 and 46, is the input-impedance 43, the terminal 46 being connected to the control-grid 7. The junction-terminal *n*, between the resistance 25 and condenser 26, is connected to terminal 44 through a switch-blade S₃; also the terminal *n* is directly connected with the terminal A₁. At 43' is a variable contactor upon the resistance 42, the contactor 43' being selectively connectable to the terminal 45 by means of the switch-blade S₄; the terminal 45 is understood to be connected to grid control elements of one or more thermionic tubes of a thermionic amplifier having its output-impedance coupled with the input-impedance 43 of tube 10, and so that conductive connection of the grid control elements of said amplifier to the respective cathodes of said amplifier is completed through the terminal 45 in a manner well understood, for example by a conductive connection of terminal 45 to the ground 36, and by conductive connection of the cathodes of said amplifier through individual voltage-bias resistors to ground 36. Uses of the switch-blades S₃, S₄, and other selector means, are hereafter illustrated. The switch-blades S₁ and S₂, are understood to be respectively connected to control-grids of a push-pull audio-frequency amplifier, through connections indicated by G₁ and G₂. The terminal A₂ is understood to be for phase-inversion, that is, to be connected through connection P₂ to the output-impedance of the audio-frequency amplifier in a manner well understood, and so as to apply between ground 36 and terminal A₂ equal voltages of opposite phase to those applied between ground 36 and terminal A₁, by the amplitude-demodulated voltages upon resistance 25.

Referring to Fig. 2, at 5a and 6a are terminals for applying the carrier currents to be demodulated. Primary coils 5 and 6 in series, are connected between the positive terminal of source 37 and the terminal 6a; the terminal 5a is connected to ground 36, and to the positive terminal of source 37 by the by-pass condenser 41' of negligible impedance for carrier frequencies, for carrying the alternating current component of currents through primary coils 5 and 6. The terminals 5a and 6a, are understood to be for connection to the output side of a thermionic amplifier for carrier currents, for example, such as illustrated at terminals 65 and 66, of amplifier 68, Fig. 3. In tube 10, suppressor-grid 9 is connected to cathode terminal 16, and screen-grid 8 is connected by variable connector 38 to a positive terminal upon source 37; by-pass condenser 40 is connected from screen-grid 8 to the cathode terminal 16. At F is an audio-frequency transformer, having primary 25a connected across a part of resistance 2, and secondary 25b with one terminal grounded to 36, and the other terminal connected to control-grid 7. The terminal A₁ is connected to terminal *n*. Terminal 45 is connected to switch-blade S₄', which is connectable either with resistance 42, or with ground 36. The anode 11 is energized by connection from the positive terminal of source 37 through switch-blade S₆, and choke-coil 78, to anode 11; also anode 11 is connected to terminal 6a through stopping condenser 77. The thermionic alternating

current conductance between anode 11 and cathode 14 is thus shunted across primary coils 5 and 6 in series, the reactance of condenser 77 being negligible in relation to said conductance, as is also the reactance of condensers 41' and 34, for carrier frequencies. An alternative connection for anode 11 can be employed, in which condenser 77 is replaced by switch-blade S₆, and the connection to the positive terminal of source 37 through choke-coil 78 omitted, the anode 11 then being directly energized from terminal 6a when the switch S₆ is closed.

Referring to Fig. 3, at 15 is a thermionic double-diode with diode-anode 12, diode-anode 13, and respective diode-cathodes 14a and 14b. Connected between the cathodes 14a and 14b are the two resistances 22' and 23' in series, the terminal 16' being a junction-terminal between series-connected resistances 22' and 23'; the terminal of resistance 23' opposite terminal 16', is grounded at 36. Shunted across resistance 22' is condenser 20', and shunted across resistance 23' is condenser 24', each condenser with respective shunted resistance providing a large time-constant in relation to the half-cycle time of the carrier currents. Connected to the terminal *a* of the resonance circuit 3—17 is the diode-anode 12, connected through conductor d', and connected to the terminal *b* of the resonance circuit 4—19 through conductor k', is the diode-anode 13. Connected between the common terminal 1 and the junction-terminal 16', is the control-impedance 21—2, carrying the sum total of the thermionic currents to diode-anode 12 and diode-anode 13. At 10a is a thermionic tube having the anode 11, cathode 14, control-grid 7, screen-grid 8, and the suppressor-grid 9. The suppressor-grid 9 is connected to the cathode 14, and screen-grid 8 is connected to a positive terminal upon the source 37 by the variable connector 38. Connected between the control-grid 7 and the terminal 44' is the input-impedance 43. Cathode 14 is connected to ground through the bias-resistance 35. The anode 11 is energized by connection through the primary coils 6 and 5 in series, to the positive terminal upon the source 37. At 68 is a thermionic amplifier for carrier frequency currents of reduced carrier frequency, and illustrated in block-diagram form, the input-terminals of the amplifier being indicated by 55 and 56, and the output-terminals of the amplifier being indicated by 65 and 66. At 54 is an output impedance for the amplifier 68 coupled with the input-impedance 43 of the demodulator, by mutual inductance between 54 and 43. At 53 is a terminal conductively connected to a control-grid of one stage of the amplifier 68, and at 59 is another terminal conductively connected to a control-grid of another stage of the amplifier 68. Terminals 58 and 59 are connected together, and to the terminal 45, it being understood that the cathodes of the amplifier 68 are connected to ground 36 through individual bias-resistances in a manner well understood, and for example such as resistance 35 connected to cathode 14; also that the anodes of the tubes of amplifier 68 which have thermionic currents controlled by the control-grids connected to terminals 58 and 59, are supplied from the source 37, for example by connection 53, and that screen-grids of the tubes of amplifier 68 may be supplied by the variable connector 38. At 43 is a mixer-device, having a thermionic alternating current generator with a bias-voltage control means for controlling the frequency of generated currents, and illustrated in

block-diagram form. At 41 is a receiving antenna connected to the mixer-device, and at 62 and 63 are output-terminals of the mixer-device, terminal 62 being connected to terminal 56, and terminal 63 being connected to terminal 55 of amplifier 68. The mixer-device is understood to supply a reduced carrier frequency to the terminals 62, 63, obtained from a combination of the generator frequency with the received frequency, received upon antenna 41; also the generator is understood to have its generated frequency controllable by the bias-voltage supplied through conductor t in a manner well understood, for example by reactance-modulator means having the conductor t and connected terminal 51 connected to a control-grid of a thermionic tube, controlling a quadrature component of current of the generator.

At F is an audio-frequency transformer having the primary winding 25a, and the secondary winding 25b. The primary winding 25a is connected across a part of the resistance 2 of the control-impedance 2-21, for transferring voltage variations from the control-impedance to the secondary 25b. It will be understood that transformer F has the usual characteristics of audio-frequency transformers, and passes a band of frequencies approximately between 100 cycles per second and 10,000 cycles per second, that the phase-shift is small over a substantial part of this range, and that the part of the resistance 2 included across the primary 25a is small in relation to the primary impedance. One terminal of the secondary 25b is connected to the ground 36, the other terminal of the secondary 25b is connected to the terminal M of a switch controlled by the switch-blade S₃₄. The switch-blade S₃₄ is connected to terminal 44' of the input-impedance 43, and terminal 44' is connected to terminal 45 of the control-grids of amplifier 68 by means of the conductor 39'.

At 75-76-74, is a second transfer-filter for transferring steady voltages, independent of amplitude-modulation, and proportional to an average amplitude of the carrier currents. The condenser 76 has one terminal connected to ground 36, and the other terminal connected through resistance 75 to the junction 16' between resistances 22' and 23'. Resistance 14 is shunted across condenser 76. The terminal V of the switch controlled by switch-blade S₃₄, is connected to resistance 14 by a variable contactor upon resistance 74. The reactance of condenser 76 is negligible at audio frequencies, in relation to the resistance of 75, and the resistance of 74. Shunted across resistance 23' is the condenser 72 connected in series with the resistance 73, one terminal of condenser 72 being connected to the junction 16'. The reactance of condenser 72 is negligible at audio frequencies in relation to the resistance of 73. At S₁ is a switch-blade for connecting the control-grid of an audio-frequency amplifier by means of connection G₁, with the terminal F₁ for frequency-demodulated voltages, or with the terminal A₁ for amplitude-demodulated voltages. Terminal A₁ is connected to the terminal of resistance 73 opposite the ground connection 36, and between the condenser 72 and resistance 73.

At 49-50 is a third transfer-filter for transferring steady bias-voltages proportional to an average frequency-deviation of the carrier currents from a centre-frequency of the resonance circuits 3-11-18, and 4-19, for automatic correction of tuning, independent of the audio-fre-

quency variations of the frequency deviations with reference to a centre-frequency of the frequency-modulated carrier currents. At 49 is a condenser connected in series with the resistance 50, one terminal of the condenser 49 being connected to the ground 36, and one terminal of the resistance 50 being connected to diode-cathode 14a, so that the series-connected resistance 50 and condenser 49 are shunted across the diode-cathodes 14a-14b. The junction-terminal 60 between the condenser 49 and resistance 50 is connected through the conductor t to terminal 61, upon the mixer-device, for transmitting bias-voltage for regulating the generated frequency of the thermionic generator of the mixer-device. The reactance at audio-frequencies of condenser 49 is negligible in relation to the resistance of 50. At 51 is a condenser connected in series with the resistance 52, the junction between condenser 51 and resistance 52 being connected to the terminal F₁, and the other terminal of resistance 52 being connected to the ground 36; the other terminal of condenser 51 being connected to diode-cathode 14a. The reactance of condenser 51 at audio-frequencies is negligible in relation to the resistance of 52.

At 78-71 is illustrated a type of ballast-impedance shunted across the resistance 22' for the purpose of equalizing any unbalance of the diode circuits introduced by employment of the impedances 75-76-74 and 72-73 shunted across the resistance 23'. It will be understood that various equivalent structures can be connected across the resistance 22'; for example, an obvious equivalent being the connection across the resistance 22' of impedances identical with those of 75-76-74, and 72-73, the resistances 22' and 23' being equal.

In Fig. 1, tuning means is shown for indicating the appropriate tuning for a centre-frequency of the resonance circuits, off-resonance from the resonant frequency of either resonance circuit by a predetermined amount, employing the control-impedance and an electron-ray tube 86. The tube 86 has cathodes 79, a control-grid 82, a luminous-indicating anode 83, and an anode-control electrode 85 for controlling electron-beams from cathode 79 to anode 83. The anode 83 is energized by conductor 80 connected to a positive terminal upon source 37, and anode 85 is energized through the resistance 81 connected to anode 83. Control-grid 82 is connected to resistance 2 by a variable contactor upon 2, and cathodes 79 are connected to the cathode terminal 16 of cathode 14.

Certain further details with reference to the operation of the control-impedance, and principles of compensation for amplitude-modulation by a dynamic balance are hereafter given, in relation to Fig. 4, and Fig. 5.

Before considering Figs. 4 and 5, some of the important features of operation of the structures will be pointed out, for Figs. 1, 2, and 3. Referring to Fig. 1, voltages are developed across the control-resistance 2, directly proportional to the amplitudes of the carrier currents in the primaries 5, 6, and independent of the frequency-deviations from a centre-frequency of the carrier currents, over the entire range in which frequency-modulation is employed. Variation voltages are developed upon resistance 25 substantially equal to the variation voltages across resistance 2, caused by amplitude variations of the carrier current through primaries 5, 6, at audio-frequencies. However, very slow changes of

amplitude of the carrier currents, produce no compensating voltages upon resistance 25. When the audio-frequency push-pull amplifier is connected with terminals F₁ and F₂, and the carrier currents in the primaries 5, 6, are frequency-modulated and have a constant amplitude, no compensating voltages are produced across resistance 25, and the differential unidirectional voltages across 23—1—22 resulting from voltage rectification and frequency-modulation, are transmitted to resistances 52, and 52'. Also, if the amplitude of the carrier currents changes at a slow rate, e. g. if the carrier current amplitude increases to double its original value in the course of thirty seconds, at a substantially uniform rate, no compensating voltage is provided upon resistance 25. When the switch-blade S₃ connects with terminal 44, as it does during reception of frequency-modulated carrier currents, compensating voltages are transmitted to the control-grid 7 if the carrier current amplitude varies at a specified rate, e. g. at a rate sufficient to cause an undesired acoustic resultant from the cross-modulation caused by variation of the carrier amplitude. It will be noted that the cathode terminal 16, of cathode 14, is positive relative to the ground 36; also that the direction of flow of rectified current through resistance 2 is from 2 to junction 1, the rectified voltage upon resistance 2 being positive at the terminal 16 with reference to terminal 1, and that an increased negative voltage is introduced upon control-grid 7 through the path 16—34—25—7 when the voltage across resistance 2 is increased by reason of an increase in the amplitude of the carrier currents through primaries 5, and 6. This increased negative bias upon control-grid 7 is capable of introducing a large decrease of mutual-conductance in the tube 10, sufficient to substantially erase the original increase in carrier current; likewise a decrease in the carrier current amplitude at an audio-frequency rate, causes a reversed flow through resistance 25, and a decreased negative-bias voltage upon control-grid 7, capable of introducing a large increase of mutual-conductance sufficient to erase the decrease of the original carrier amplitude. The input-impedance 43 is understood to be coupled with the output-impedance of an amplifier for amplifying carrier currents, or carrier currents of reduced frequency, such as the amplifier 68, Fig. 3, and the compensating voltage upon resistance 25 may also be employed to change the mutual conductance of the tubes of this amplifier, to attain a very high rate of change of mutual-conductance in relation to incremental voltage upon control-resistance 2, or resistance 25. For example, the control- grids of amplifier 68 connected to terminal 45, can be connected to terminal 44 by the connector 39. The switch S₅—39a is omitted when the connection 39 is employed. When it is desired to receive amplitude-modulation, switch-blades S₁, S₂, S₃, and S₄, are deflected to a downward position so as to connect respectively with the terminals A₁ and A₂, so as to open the circuit from terminal n to terminals 44 and 45 through switch-blade S₃, and so as to connect the switch-blade S₄ with the terminals 44 and 45. With these connections amplitude-modulation produced across resistance 2 is transmitted to terminal A₁ from resistance 25; also the steady bias-voltages from resistance 42 are introduced upon control-grid 7, and upon the control- grids of the amplifier 68 in relation to the amplitude of the carrier currents. It will be noted that impedance 27—28

is in parallel with resistance 2 for the flow of currents from terminal 16 to the terminal 1, and that the voltage across condenser 28, for example by traversing the path from terminal 16 through resistance 2 and resistance 27, is composed of a steady voltage, and equal and opposite variation voltages, the latter voltages annulling each other; resistance 42, and contactor 43' being provided to proportion the magnitude of steady voltage employed between terminal 16 and variable contactor 43'. With this particular connection, the bias-voltage from resistance 35 is eliminated from the control-grid 7, only the negative bias-voltage from terminal 1 through resistance 42 to contactor 43' being upon control-grid 7, and increasing in relation to the amplitude of the unmodulated carrier currents, i. e. increasing in relation to the average amplitude of the amplitude-modulated carrier currents; the bias-voltage however upon the control- grids of the amplifier 68 is relative to the ground 36, and the bias-voltage from terminal 45 to terminal 16, is opposed to the bias voltage from terminal 16 to ground 36. Thus, resultant negative bias-voltage upon the control- grids of the amplifier 68 is not operative until the amplitude of the carrier currents exceeds a predetermined minimum value, after which increased carrier amplitudes operate to reduce the mutual-conductance, and control the demodulated output-voltage upon A₁.

Other selective means for employing the transfer-filters, will be evident. For example, the conductor 39 may be omitted, and a switch S₅—39a employed, in which switch-blade S₅ is connected to the ground 36, and terminal 39a connected to terminal 44, the switch being open for frequency-demodulation and closed for amplitude-demodulation. With this connection, no amplitude-modulation compensating voltages are employed upon the amplifier 68, and when receiving amplitude-modulation intelligence bias-voltage of resistance 35 is operative upon control-grid 7. Control voltages for controlling maximum strength of the amplitude-demodulated output voltages are then only applied to the control- grids of the amplifier 68, the switch-blade S₄ being permanently closed upon the switch-terminal connected with terminal 45. Maximum strength of output voltages is then regulated both for frequency-demodulated voltages and amplitude-demodulated voltages. Still other combinations will be evident to anyone skilled in the art, for employing the transfer-filters selectively with the control-grid 7, and the control grids of amplifier 68. Tuning of the resonance circuits of Figs. 1 and 2, will be apparent from the consideration hereafter, of Fig. 4.

In the operation of Fig. 2, anode 11 is energized through switch-blade S₆ only when reception of frequency-modulation is desired; when amplitude-modulation is selected the switch-blade S₆ is disconnected from the positive terminal of source 37. When frequency-modulation is selected for reception, amplitude-modulation compensating voltages are impressed upon control-grid 7 from the secondary 25b. The equivalent impedance of the primary circuit 5 and 6, is substantially pure resistance for a range of frequencies including the operating range of frequency-modulation, as will be evident from consideration of Fig. 4, and the alternating current conductance of tube 10 between cathode 14 and anode 11, is shunted across coils 5 and 6 by way of the circuit 6a—77—11—14—34—36—41', the reactances of condensers 77, 34, and 41' being

negligible in relation to the thermionic resistance 11-14. In this circuit the fixed negative bias-voltage determining the normal mutual-conductance of tube 10 is supplied from resistance 35, and the order of connection of the secondary 25b is such that when the currents through resistance 2 are increased by an increase in carrier current amplitudes a positive bias-voltage is introduced upon the control-grid 7, increasing the conductance between cathode 14 and anode 11, and reducing the carrier current through the primaries 5 and 6. For the reception of amplitude-modulation the switch-blade S_{4'} is deflected to the downward position, connecting the terminal 45 with the resistance 42, and providing control of maximum demodulated output voltages. In the upward position of switch-blade S_{4'}, the terminal 45 is connected to the ground 36.

In the operation of Fig. 3, for reception of frequency-modulation terminal F₁ connects with switch-blade S₁, and terminal M connects with switch-blade S₃₄. Compensation of amplitude-modulation is provided by the bias-voltages introduced upon the control-grid 7, and upon the control-grids of amplifier 68 by the secondary 25b of audio-frequency transformer F. The order of secondary connection is such as to increase the amount of negative bias-voltage upon the control-grid 7 when the current through control-resistance 2 increases through increase of amplitude of carrier currents in the primaries 5 and 6. For reception of amplitude-modulation, the switch-blade S₁ is connected with terminal A₁; and the audio-frequency voltages superposed upon the rectified voltages on resistance 23' are taken off from resistance 13, one terminal of which is connected to ground 36. Switch-blade S₃₄ is connected with terminal V, and steady negative bias-voltages are taken off from resistance 74 for control of maximum amplitude-demodulated output voltages, in relation to the amplitudes of applied carrier currents.

During reception of frequency-modulation, the differential rectified voltages between cathode 14a and cathode 14b are taken off from the resistance 52, one terminal of which is grounded at 36.

It will be noted that only when the frequency of the carrier currents coincides with the centre-frequency of the resonance circuits, that is, with a frequency mid-way between the individual resonant frequencies of the resonance circuits, will the voltage between the cathodes 14a and 14b be zero for the balanced diode circuits. When the carrier current frequency does not coincide with the centre-frequency of the resonance circuits, then a constant difference of potential exists between the cathodes 14a and 14b. If this carrier current is frequency-modulated at audio-frequencies, then in addition to the constant difference of potential which is an index of the deviation between the carrier frequency and the centre-frequency of the resonance circuits, there is present an audio-frequency component of voltage. When such a demodulator is intended only for amplitude-demodulated voltages, the frequency-deviation between the carrier frequency and the centre-frequency of the resonance circuits, due to mistuning, is not subject to rapid changes, and the resultant substantially constant difference of potential between the cathodes 14a and 14b can be directly applied to the conductor t and terminal 61, to automatically correct the mistuning. If directly applied however, when frequency-demodulated voltages from a frequency-modulated carrier are present between cathodes

14a and 14b, undesired frequency-modulation at audio-frequencies would be introduced into the receiver.

An important feature of Fig. 3, is the means for providing steady bias-voltages for automatic correction of small amounts of mistuning, in a receiver for frequency-modulated carrier currents. Condenser 49 in series with resistance 50 is shunted across the cathodes 14a and 14b; variation voltages between the junction 60 of condenser 49 and resistance 50, and the ground 36, are therefore of opposite phase, in the circuit 60-50-22'-23'-36, so that only the steady resultant voltage is applied to conductor t, to modify the generated frequency to bring the carrier current centre-frequency into coincidence with the centre-frequency of the resonance circuits. It will be evident that provision of a capacity differential between the tuning condensers 17 and 19, for example by a spacer-condenser 18, can be made either upon resonance circuit 3-17 as illustrated, or upon resonance circuit 4-19, thus determining the polarity of the cathode 14a relative to ground 36, and relative to positive or negative deviations of carrier frequency from the centre-frequency of the resonance circuits, for purposes of compensating these frequency-deviations.

Referring to Fig. 4, graphs are illustrated, the horizontal axis or abscissas indicating frequencies. At I₁ is shown a resonance curve for rectified currents in the diode circuit through the resonance circuit 3-17, through resistance 22 and resistance 2; at I₂ is shown a resonance curve for rectified currents in diode circuit through the resonance circuit 4-19, through resistance 23 and resistance 2. The above applies also to Fig. 3, resistances 22' and 23' of Fig. 3 replacing 22 and 23, respectively. At f₁ is indicated the resonant frequency for resonance circuit 3-17, and at f₂ is indicated the resonant frequency for the resonance circuit 4-19. Midway between f₁ and f₂ is the centre-frequency f_c of the resonance circuits. In Fig. 4 the frequency-deviations are indicated by Δf_0 and Δf_0 respectively, for the differences $f_c - f_1$ and $f_c - f_2$, sufficient to de-phase the alternating currents in circuits 4-19 and 3-17 by 45 degrees. At p is indicated the intersection of the resonance curves I₁ and I₂. At I_{1'} and I_{2'} are indicated respectively tangent lines to the curves I₁ and I₂, through the point p; these lines provide a substantial coincidence with the respective curves I₁ and I₂, and for a range of frequency-deviations Δf and $-\Delta f$ from the centre-frequency somewhat less than one half of Δf_0 . It will be noted that within this range, an increase of current I₁ is accompanied by an equal decrease of current I₂ as the frequency is varied, and that the sum of the currents I₁+I₂ is constant, and independent of the frequency modulation.

In order to aid in a better understanding of the principles of operation of the control-impedance 2-21 with reference to tuning, and as an index of amplitudes of carrier currents, and the principles of operation of the dynamic balance means for annulling undesired amplitude-modulation during reception of frequency-modulation, the following quantitative relations are pointed out in a simplified form, it being understood that these indicated relationships are not to be construed as any manner of limitation upon the structures disclosed, or otherwise than to facilitate a better understanding of the devices.

The curves I₁ and I₂ may also be taken to indicate the respective alternating voltages across the

resonance circuits 3—17 and 4—19. If these respective voltages are indicated by E_a and E_b , and the amplitude of the carrier currents in the primary coils 5 and 6 is indicated by I_p , then the voltages E_a and E_b within the above-stated range of frequency-deviations are:

$$E_a = BI_p(1 - K\Delta f) \quad (1)$$

$$E_b = BI_p(1 + K\Delta f) \quad (2)$$

from well known circuit relations for the coupled resonance circuits, the constants B and K are readily shown to be related to the circuit factors as follows:

$$B = \sqrt{2\pi \cdot f_c \cdot M \cdot Q} \quad (3)$$

and

$$K = \frac{Q}{f_c} \quad (4)$$

wherein Q is the reactance-resistance ratio of the coil 3 or coil 4 of the resonance circuits, and M is the mutual inductance between the primary 5 and coil 4, or the primary 6 and coil 3. In terms of the rectified currents, the foregoing voltages can be indicated with reference to the corresponding resistances of the diode circuits. Designating by R_0 the resistance of the control-resistance 2, and by R the resistance of 22 or 23 Fig. 1 or 2, and of 22' or 23', Fig. 3, then:

$$E_a = R_0 I_0 + R I_1 \quad (5)$$

and

$$E_b = R_0 I_0 + R I_2 \quad (6)$$

Thus

$$E_a + E_b = I_0(2R_0 + R) = 2BI_p$$

wherein the total current through control-resistance 2, is $I_0 = I_1 + I_2$. The total rectified current through resistance 2, in terms of the primary current, or carrier current I_p , is therefore indicated by:

$$I_0 = \frac{2B}{2R_0 + R} I_p \quad (7)$$

The control voltage is $R_0 I_0$, and the dependence of this control voltage upon carrier current amplitude, and independence of frequency-modulation is indicated.

The frequency-demodulated voltages available are indicated by:

$$E_b - E_a = 2BK I_p \Delta f \quad (8)$$

and from (5), (6),

$$E_b - E_a = R(I_2 - I_1) \quad (9)$$

In Fig. 4, the maximum rectified currents are indicated by I_{1m} and I_{2m} respectively, for the currents I_1 and I_2 . The points q and s , are corresponding points upon the curves for I_2 and I_1 respectively, for a positive frequency-deviation of the carrier frequency from the centre-frequency. The dotted-line curve shows total current through the control-resistance 2, for a range of frequencies far removed from the centre-frequency of the resonance circuits, and corresponding unidirectional voltages across the resistance 2. Within the range of frequency-modulation, the voltage across resistance 2 is indicated by E_0 ; the additional voltage across resistance 22 by E_1' , for the point s , and the additional voltage across resistance 23 by E_2' , for the point q . The total voltages for the points s and q , being respectively:

$$E_a = E_0 + E_1', \text{ and } E_b = E_0 + E_2'$$

and the voltage difference

$$E_b - E_a = E_2' - E_1'$$

Referring to Fig. 1, utilization of the negative bias-voltage established between the cathode terminal 16 and a point upon the control-resistance

2, for tuning the carrier frequency to coincidence with the centre-frequency of the resonance circuits, is shown, with reference to Fig. 4. This negative bias-voltage is a maximum for the coincidence of the carrier frequency, or centre-frequency of frequency-modulated carrier currents, with the centre-frequency of the resonance circuits, as indicated by f_c . As the system is tuned by varying the mechanically connected condensers, the intermediate position between the two positions for which a falling off of negative bias-voltage is evident, is the position corresponding to exact tuning. It will be understood that the various selector switches described herein, can be readily connected mechanically, so that but a single switching operation is needed to switch from a position for reception of amplitude-modulation, to a position for reception of frequency-modulation. Since this type of receiver must provide switching means for selecting either amplitude-modulation or frequency-modulation, it will be evident that an intermediate position of the switching means may be employed for a tuning position, wherein the audio-frequency amplifier connections G_1 , G_2 are open, and whereby intermediate contacts are provided to properly ground to 36 the control-grid terminal 44 and control-grid terminal 45 of amplifier 68, eliminating for example, the connection of these control grids with resistance 42, and the bias control-voltage upon resistance 42.

Referring to Fig. 5, a mutual-conductance characteristic is indicated by g_m , with reference to negative bias-voltages along the axis of abscissas, for a super-control type of tube such as may be employed for the tube 10, or 10a. At g_{m0} is indicated a normal value of the mutual-conductance, established for example by a bias-voltage $-E_c$, provided by flow of current through resistance 35. At Δg_m is indicated a positive increment of the mutual-conductance established for example by a decrease of current through control-resistance 2, and similarly at $-\Delta g_m$ is a negative increment established by an increase of current through resistance 2. The principles of the dynamic balance employed for compensation of undesired amplitude-modulation, i. e. for substantially annulling amplitude-modulation upon the demodulators, are hereafter stated in simplified form.

The impedance of tube 10, or 10a, is usually large in comparison with the load impedance of primaries 5 and 6, so that the amplitude of the carrier currents I_p through the primaries is normally indicated by the relation: $I_p = g_{m0} E_g$, in which E_g is the amplitude of the carrier voltage impressed upon a control-grid, for example control-grid 7. Without any compensation for amplitude-modulation, the mutual-conductance is constant and $g_m = g_{m0}$. Designating the uncompensated carrier current through primaries 5 and 6, as I_{p0} , and the uncompensated carrier voltage upon the control-grid as E_{g0} , then:

$$I_{p0} = g_{m0} E_{g0} \quad (10)$$

and

$$\Delta I_{p0} = g_{m0} \Delta E_{g0} \quad (11)$$

in which ΔI_{p0} is the change in carrier current amplitudes due to amplitude modulation, and ΔE_{g0} the corresponding change in carrier voltage. The amplitude-modulation index is

$$m_0 = \frac{\Delta E_{g0}}{E_{g0}} = \frac{\Delta I_{p0}}{I_{p0}} \quad (12)$$

for uncompensated carrier current or voltage.

However, with compensation by mutual-conductance variation, controlled by the amount of amplitude-modulation, the resultant increment of primary carrier current amplitude is defined as follows:

$$(I_{p0} + \Delta I_p) = (g_{m0} + \Delta g_m) (E_{g0} + \Delta E_{g0})$$

from which the resultant current amplitude increment is:

$$\Delta I_p = g_{m0} \Delta E_{g0} + \Delta g_m (E_{g0} + \Delta E_{g0}) \quad (13)$$

Also, due to the transfer-filter means between the output side and input side of tube 10, or 10a, transferring only amplitude-modulation voltages derived from ΔI_p , to modify the mutual-conductance:

$$\frac{\Delta g_m}{\Delta I_p} = -D \quad (14)$$

From (13) and (14) the reduction in amplitude-modulation index as a consequence the structures heretofore disclosed, is derived. Thus: The resultant compensated carrier current increment is

$$\Delta I_p = \Delta I_{p0} - D \Delta I_p (E_{g0} + \Delta E_{g0})$$

or

$$\Delta I_p \left[1 + DE_{g0} \left(1 + \frac{\Delta E_{g0}}{E_{g0}} \right) \right] = \Delta I_{p0} \quad (15)$$

Equation 15 gives the change of carrier amplitude remaining after compensation, in relation to the original uncompensated change of carrier amplitude; defining the compensated modulation-index as

$$m_c = \frac{\Delta I_p}{I_{p0}}$$

then from Equation 15:

$$m_c = \frac{m_0}{[1 + DE_{g0}(1 + m_0)]} \quad (16)$$

Equation 16 illustrates the effectiveness, in reducing the undesired amplitude-modulation, of the structures herein disclosed. It will be evident, that when the mutual-conductance of several initial stages of amplification is also controlled, the resultant effective change of mutual-conductance with change of unidirectional current through the control-impedance 2 is greatly increased, that is, a large value of D is provided. As an illustration of the operation with reference to Equation 16, if sufficient negative bias-voltage is produced upon the control-resistance 2 with a positive increment of carrier current corresponding to 10 percent amplitude-modulation, to make a change of effective mutual-conductance substantially equal to $-g_{m0}$, then

$$D = \frac{g_{m0}}{\Delta I_p} = 10 \frac{g_{m0}}{I_{p0}}$$

and

$$m_c = \frac{m_0}{1 + 10(1 + m_0)}$$

under which conditions an amplitude modulation of 70 percent would be reduced by the compensation to about 4 percent. For a negative increment of carrier current, values of the coefficient D may be three or four times larger than the above illustrative value. It will be noted that the change of carrier current amplitude, indicated by ΔI_p , only provides a modification of mutual-conductance when the rate of change of ΔI_p is sufficiently rapid to come within the audio-frequency range, that is, when the changes in the envelope of the carrier frequency currents are at an audio-frequency.

Reference for example to Equation 8, for the sensitivity of the frequency-demodulator for providing demodulated voltages in relation to the amount of frequency deviations, shows that the primary current I_p is a factor. Thus changes of I_p cross-modulate the frequency-demodulated voltages, however, it is evident that only such changes as occur at a sufficiently rapid rate would be objectionable. Gradual changes of I_p , merely have the effect of increasing or decreasing the strength of the demodulated output voltages, and the acoustic output. This is an important feature of this invention, eliminating the necessity of continual readjustment of a balance, as required in compensating systems for amplitude-modulation wherein a static balance is determined by the absolute magnitude of the carrier currents, not permitting any change without readjustment.

With reference to Figs. 1 and 2, it will be evident that an alternative transformer coupling can be used from the demodulator to the audio-frequency amplifier; with this connection the connections of F_1 , F_2 , and ground 36 to resistances 52, 52', are omitted, the primary of the coupling transformer being shunted across the resistances 52 and 52' in series, one terminal of the secondary being connected to F_1 , the other terminal of the secondary being connected to terminal F_2 , and a centre-tap terminal of the secondary being connected to the ground 36.

Having described several illustrative embodiments of my invention, it will be evident that changes can be made in the form and arrangement of parts, and by substitution in part of other well known structures, or otherwise, without departing from the spirit of my invention, as set forth in the appended claims, and I do not therefore limit the scope of the invention to such particular embodiments, or otherwise than by the terms of the appended claims.

What is claimed is:

1. In a frequency demodulator for demodulating frequency-modulated carrier currents, resonant circuit means for determining alternating voltages responsive to frequencies of said carrier currents, and responsive to amplitudes of said carrier currents, a first voltage-rectifying means including a first thermionic diode means serially connected with a first resistance, a second voltage-rectifying means including a second thermionic diode means serially connected with a second resistance equal to said first resistance, a connection from a first terminal upon said resonant circuit means to said first rectifying means, a connection from a second terminal upon said resonant circuit means to said second rectifying means, a common connection between said first and second rectifying means, a connection from a third terminal upon said resonant circuit means to said common connection including a control-impedance carrying the sum total thermionic currents of both diode means; an output-impedance for frequency-demodulated voltages connected to said first and second resistances, thermionic amplifier means including control-grid means energizing said resonant circuit means with amplified carrier currents, and transfer-filter means coupling said control-impedance with said control-grid means, transferring compensating voltages to said control-grid means, substantially annuling amplitude-modulation of said carrier currents at audio-frequencies, and permitting carrier current amplitude variations at lower sub-audio-frequencies.

2. In combination with the structure of claim 1, a second transfer-filter means including a filter-condenser and filter-resistance, selectively connectable with said control-grid means, selectively applying negative bias-voltage to said control-grid means proportional to an average amplitude of said carrier currents, independent of said audio-frequencies, for regulating amplitudes of demodulated voltages upon said demodulator.

3. In combination with the structure of claim 1, filter means including a serially connected filter-condenser and filter-resistance connected to terminals of said first and second resistances, and conductive circuit connections through said filter-resistance and said first and second resistances, providing steady bias-voltage independent of audio-frequency variations of said frequency-demodulated voltages, and proportional to frequency deviation of the centre-frequency of said carrier currents from the centre-frequency of said resonant circuit means, for modifying the centre-frequency of said carrier currents to coincide with said centre-frequency of said resonant circuit means.

4. In a frequency-demodulator device for demodulating frequency-modulated carrier currents, resonant circuit means determining alternating voltages responsive to frequencies of said currents, and responsive to amplitudes of said currents, voltage-rectifying means connected with said resonant circuit means, including a thermionic double-diode with a first anode, a second anode, and a common cathode, and a conductive impedance connected between said resonant circuit means and said common cathode, carrying the sum total thermionic current of both said anodes, said conductive impedance including a resistance shunted by a condenser; an output-impedance for frequency-demodulated voltages connected to said anodes, thermionic amplifier means energizing said resonant circuit means with amplified carrier currents, including said common cathode and a control-grid means, and a transfer-filter means coupling said resistance with said control-grid means, transferring compensating voltages to said control-grid means, substantially annulling amplitude-modulation of said carrier currents at audio frequencies, and permitting amplitude variations of said carrier currents at lower sub-audio frequencies.

5. In combination with the structure of claim 4, a second filter means coupled with said voltage-rectifying means, providing steady negative bias-voltage proportional to average amplitude of said carrier currents, independent of said audio frequency amplitude-modulation, and selector means for selectively transferring to said control-grid means said compensating voltages, or said steady negative bias-voltage.

6. In a receiver for frequency-modulated and amplitude-modulated carrier waves, a frequency-demodulator device for demodulating frequency-modulated carrier currents, having a first resonance circuit, a second resonance circuit resonant at a frequency interval from the resonant frequency of said first resonance circuit, a first primary coil coupled with said first resonance circuit, a second primary coil coupled with said second resonance circuit, a first voltage-rectifying means including a first thermionic diode means serially connected with a first resistance, a second voltage-rectifying means including a second thermionic diode means serially connected with a second resistance equal to said first resistance, a common connection between said first and sec-

ond rectifying means, a connection from said first resonance circuit to said first rectifying means, a connection from said second resonance circuit to said second rectifying means, a common terminal upon said first and second resonance circuits, and a control-impedance connected from said common terminal to said common connection, carrying the sum total of thermionic currents of both said diode means; an output-impedance for frequency-demodulated voltages connected to said first and second resistance, thermionic amplifier means coupled with said first and second primary coils, including grid control means, controlling the amplitude of carrier currents through said primary coils, and transfer-filter means coupling said grid control means with said control-impedance, transferring compensating voltages to said grid control means, substantially annulling amplitude-modulation of said carrier currents at audio frequencies, and permitting carrier current variations at lower sub-audio frequencies.

7. In combination with the structure of claim 6, a second transfer-filter means including a filter-condenser and a filter-resistance, for transferring to said grid control means a steady negative bias-voltage, proportional to an average amplitude of said carrier currents, independent of audio frequency modulation of said carrier currents, and selector means for selecting frequency-demodulated or amplitude-demodulated voltages from said demodulator, including a switching means for interrupting said coupling of said transfer-filter means with said grid control means.

8. In combination with the structure of claim 6, said receiver having a mixer-device coupled with said grid control means, for reducing the carrier frequency of said carrier waves, including a thermionic alternating current generator with bias-voltage control means for controlling the frequency of said generator, said demodulator device having a second transfer-filter means comprising a filter-resistance and a filter-condenser connected in series and connected between a terminal of said first resistance and a terminal of said second resistance, providing a conductive path comprising said filter-resistance, said first resistance, and said second resistance in series, and the circuit connections of said conductive path in series with said bias-voltage control means, whereby a steady bias-voltage is provided in said conductive path for modifying said reduced carrier frequency to coincidence with a frequency midway within said frequency interval, independent of frequency-modulation of said carrier currents at audio frequencies.

9. In a frequency-demodulator for demodulating frequency-modulated carrier currents, a first resonance circuit, a second resonance circuit resonant at a frequency-interval from the resonant frequency of said first resonance circuit, coupling means coupled with said first and second resonance circuits for coupling said circuits with said carrier currents, a first voltage-rectifying means including a first thermionic diode means serially connected with a first resistance, a second voltage-rectifying means including a second thermionic diode means serially connected with a second resistance equal to said first resistance, a first common terminal upon said first resonance circuit and said second resonance circuit, a connection from said first resonance circuit to said first rectifying means, a connection from said second resonance circuit to said second rectifying means, a second common terminal

upon said first and second rectifying means, and a control-impedance connected between said first and second common terminals, carrying the sum total of thermionic currents of both said diode means, including a control-resistance shunted by a control-capacitance, providing a large time-constant in relation to the half-cycle time of said carrier currents, whereby unidirectional control-voltages are provided upon said control-resistance, proportional to amplitudes of said carrier currents, and independent of frequency-deviations over a range of positive and negative frequency-deviations from a carrier frequency midway within said frequency-interval.

10. In combination with the structure of claim 9, the tuning means for simultaneously tuning said first and second resonance circuits for resonant frequencies differing respectively from the unmodulated carrier frequency of said carrier currents by equal predetermined frequency-intervals, respectively above and below said unmodulated carrier frequency, said tuning means including the connection of a voltage-indicating device to said control-impedance, and the mechanical inter-connection of the tuning elements of each of said resonance circuits.

11. In combination with the structure of claim 9, thermionic amplifier means including grid control means and said coupling means, and a second coupling means coupling said control-impedance with said grid control means, transferring compensating voltages to said grid control means, substantially annulling amplitude-modulation of said carrier currents.

12. In combination with the structure of claim 9, thermionic amplifier means including grid control means and said coupling means, and a transfer-filter means coupling said control-impedance with said grid control means, transferring steady negative bias-voltage to said grid control means, independent of amplitude-modulation of said carrier currents, and proportional to an average carrier current amplitude, for regulating the magnitude of demodulated voltages upon said demodulator.

13. The compensating device for compensating undesired amplitude-modulation of carrier currents, in a frequency-demodulator for converting frequency-modulated carrier currents into amplitude-modulated output-voltages, said demodulator having resonant circuit means responsive to frequency-modulation and amplitude-modulation of impressed carrier currents, voltage-rectifying means including a thermionic diode and connected resistance, providing unidirectional voltages upon said resistance directly proportional to amplitudes of said carrier currents and independent of frequency-modulation of said carrier currents, and thermionic amplifier means coupled with said resonant circuit means, including a thermionic tube with grid means for controlling carrier currents impressed upon said resonant circuit means, said compensating device having a transfer-filter coupled with said resistance and with said grid means, transferring compensating voltages to said grid means substantially annulling amplitude-modulation of said carrier currents only when said amplitude-modulation is within an audio frequency range, and permitting variations of amplitude of said carrier currents when said variations are within a sub-audio frequency range.

14. In combination with the structure of claim 13, a second transfer-filter coupled with said rectifying means, and selector means for selectively

coupling said transfer-filters with said grid means, said second transfer-filter including a filter-condenser and a filter-resistance, determining steady negative bias-voltages across said filter-condenser proportional to an average amplitude of said carrier currents, independent of audio frequency amplitude-modulation of said carrier currents.

15. In a superheterodyne receiver for receiving frequency-modulated carrier waves, having a mixer-device for reducing the frequency of said carrier waves, including a thermionic alternating current generator with a bias-voltage control means for controlling frequency of said generator; and a frequency-demodulator for converting amounts of frequency-deviation from a centre frequency of said reduced carrier wave into directly proportional amounts of resultant output-voltages, of opposite polarity for positive frequency-deviations in reference to polarity for negative frequency-deviations, including an output-resistance shunted by capacitance for said resultant output-voltages and resonant circuit means tunable in relation to said centre frequency, a transfer-filter means comprising a filter-resistance and a filter-condenser connected in series and shunted across said output-resistance, providing a conductive path through said filter-resistance and said output-resistance in series, and the circuit connections of said conductive path in series with said bias-voltage control means, whereby steady compensating voltage is provided upon said bias-voltage control means, independent of audio-frequency amplitude-variations of said output-voltage, to establish a coincidence of tuning of said resonant circuit means with said centre frequency.

16. The combination with a frequency-demodulator for demodulating frequency-modulated carrier waves, of an amplitude-envelope stabilizing device for substantially removing amplitude-envelope modifications with rates of change in an audio-frequency range, said demodulator having a first output-impedance for frequency-demodulated output-voltages from constant-amplitude frequency-modulated carrier waves, and means for energizing said first output-impedance from said carrier waves including a thermionic amplifier having grid control means for controlling said carrier waves, said device including a second output-impedance for amplitude-demodulated output-voltages energized from said thermionic amplifier, and transfer-filter means connected to said second output-impedance and to said grid control means, including impedance means capable of transferring voltages sufficient for modifying the transconductance of said amplifier controlled by said grid control means, only when said rates of change of the carrier amplitude-envelope are above a sub-audio threshold range, to suppress the amplitude-modulation stimulus applied to said second output-impedance.

17. The combination with a demodulator for demodulating frequency-modulated and amplitude-modulated carrier waves, of an amplitude-modulation-reducing device for substantially annulling amplitude-modulation upon a frequency-modulated carrier wave, said demodulator having a first output-impedance for frequency-demodulated voltages, a second output-impedance for amplitude-demodulated voltages, and means for energizing said impedances from said carrier waves including a thermionic tube with grid control means for controlling said carrier waves, said

device having a transfer-filter connected with said second output-impedance and connected to said grid control means, including impedance means for transferring to said grid control means amplitude-modulation annulling voltages only when the frequency of said amplitude-modulation voltages is above a sub-audio threshold range of frequency.

18. A frequency-demodulator having a thermionic tube with a cathode, an anode, grid control means for controlling thermionic currents between said anode and cathode, a first diode-anode with said cathode and a second diode-anode with said cathode, an input-impedance connected between said grid control means and said cathode, a three-branch network having a common junction, a first branch including a first resonance

5 circuit connected in series with a first impedance between one of said diode-anodes and said junction, a second branch including a second resonance circuit detuned relative to said first resonance circuit connected in series with a second impedance between the other of said diode-anodes and said junction, and a third branch including a control-impedance connected between said cathode and said junction; coupling means coupling 10 said anode with said resonance circuits and with a source of unidirectional anode-supply voltage, and circuit connections for transferring frequency-demodulated voltages from said network including a terminal upon each of said impedances of said first and second branches.

EDWARD H. LANGE.
